Primary Examiner — Sandra Snapp*Assistant Examiner* — Jeffrey J Kemp(74) *Attorney, Agent, or Firm* — Sand, Sebolt & Wernow Co., LPA(57) **CLAIM**

The ornamental design for a chair as shown and described.

DESCRIPTION

FIG. 1 is a rear, top, left side isometric perspective view of a chair in accordance with my design;

FIG. 2 is a rear elevation view thereof;

FIG. 3 is a right side elevation view thereof;

FIG. 4 is a left side elevation view thereof; and,

FIG. 5 is a bottom plan view thereof.

The even spaced broken lines shown in the drawings represent portions of the chair that form no part of the claimed design. The dot-dot-dashed broken lines shown in the drawings represent the boundary of the claimed design and form no part thereof.
